UNITED STATES PATENT OFFICE

2,599,465

METHOD AND APPARATUS FOR THE APPLICATION OF MATERIALS

Samuel Letvin, Philadelphia, Pa., and George P. Haynes, Rockville Centre, N. Y., assignors to Thermo Projects, Inc., New York, N. Y., a corporation of New York

Application August 8, 1946; Serial No. 689,158

12 Claims. (Cl. 299—86)

1

This invention relates to the application to selected areas of insecticides, fungicides, repellents, hormones and other substances.

The invention provides an entirely new and unique method and apparatus for fractionating such materials to the state of aerosols and applying them in the form of a fog, as distinguished from the previously employed systems of dusting and spraying.

In carrying out the invention, the formulation, whether a liquid solution, or a solid material suspended in a liquid, is atomized mechanically by being introduced while in rapid rotation into a blast of heated air. The formulation becomes an aerosol or fog of particles of predetermined size, which quickly surround and cling to all objects in their path and penetrate the smallest crevices. With this system, the formulation is deposited evenly, widely and rapidly, thus providing economy of operation, both from the standpoint of the use of a minimum of formulation and labor of application.

The nature of the invention will be understood from the following description when considered in connection with the accompanying drawings, forming a part thereof, and in which:

Fig. 1 is a view in side elevation of a machine embodying and for carrying out the invention.

Fig. 2 is a plan view of the machine.

Fig. 3 is a vertical sectional view of the atomizer and universal joint on line 3—3 of Fig. 2.

Fig. 4 is a plan view of the universal joint shown in Fig. 3.

Fig. 5 is a transverse sectional view through the atomizer on line 5—5 of Fig. 3.

Fig. 6 is a sectional view on line 6—6 of Fig. 4.

Fig. 7 is an elevational view with parts in section of the insecticidal container for the machine.

Fig. 8 is a sectional view on line 8—8 of Fig. 7.

Fig. 9 is a sectional view on line 9—9 of Fig. 7, and

Fig. 10 is a control diagram of the machine.

Like characters of reference refer to the same or to similar parts throughout the several views.

The applicator illustrated, includes an atomizer supported on a mounting for universal movement, means for supplying hot air under pressure to the atomizer, and means for supplying the formulation to the atomizer where it is divided into

2

minute particles and is ejected into the atmosphere to form a fog. The size of the particles may be varied by changing the rate of flow of the formulation, and the quantity, pressure and temperature of the gases. The particles are fractionated to the aerosol size range thus permitting them to be carried by air currents for relatively long distances and to provide a uniform deposition of the material over large areas. Other elements and features of the applicator will appear as the detailed description proceeds.

Referring to the drawings, the applicator has a base 11, Fig. 1, upon which is mounted a fuel tank 12 which provides the foundation for the several parts of the machine. Fuel is supplied to the tank 12 through a combined fill and reservoir 13, Figs. 1 and 10, disposed at the upper end of a fill pipe 14, and having a removable cap 15. Fuel is withdrawn from the tank 12 through line 16, Fig. 10, by pump 17 through a screen 18 and a valve 19, and is forced through line 20 through a relief valve 21 and through line 22 into the upper portion of reservoir 13, wherein the fuel normally stands at the level of the upper end of the fill pipe 14. A fuel pressure gage 23 is connected to the lower part of relief valve 21. The fuel flows from the lower part of reservoir 13 through line 24 into the carburetor 25, of an internal combustion engine 26 which is the source of power of the machine. The engine 26 is started by turning of the wheel 27, Fig. 2, on one end of the crank shaft 28 by a rope or belt 29. The other end of the crank shaft has fixed to it a gear 30 which meshes with and drives a gear 31 on the shaft of a blower 32, Figs. 1, 2 and 10, which forces air through a duct 33 into the lower end of a combustion chamber 34 which is disclosed and claimed in the application for patent of Claude A. Bonvillian, Ralph C. Brierly and Samuel Letvin, Serial No. 479,010, filed March 13, 1943, now patent No. 2,500,925. The outer shell of the combustion chamber 34 is cylindrical and the combustion space 35, Fig. 10, is defined by a plurality of metallic frustoconical bands 36 spaced from the inner wall of the outer shell to provide an annular air space 37 into one end of which the duct 33 discharges. Adjacent ends of the bands 36 overlap in spaced relationship so that air is supplied to the combustion space at

intervals throughout its length in addition to being supplied at the ignition end. Fuel is conducted from the relief valve 21 to the nozzle 38 through line 39 having a control valve 40. The fuel introduced into the combustion chamber is ignited by a spark plug 41 to which current is supplied through wire 42 by a magneto 43, Figs. 2 and 10, coupled to the fuel pump 17, both of which are driven by a gear 44 which meshes with and is driven by gear 31. The pressure of the air introduced into the combustion chamber is indicated by an air pressure gage 45 connected with the air duct 33.

Hot air mixed with the products of combustion of the fuel consumed in the combustion chamber, flowing from the combustion space of the chamber 34 passes through a duct 46 into an atomizer 47 to which insecticidal or other treating material is supplied through a pipe 48, Fig. 3. As there is ordinarily a large excess of air passing through the combustion chamber, the proportion of products of combustion is relatively small and for convenience the hot gases passing into the atomizer may be referred to as "hot air." If an air heater were used in which the combustion did not take place directly in the heating chamber then only pure air would be supplied. The presence of the products of combustion is however immaterial. Pipe 48 discharges the treating material or formulation into a nozzle 50 having at its discharge end portion, a series of discharge orifices 51 arranged radially to the nozzle axis, through which the material is discharged into the rear portion of a stationary atomizing cup 52 having a series of tangentially disposed air passages 53 at the rear portion of the cup through which hot air is introduced into the cup and is caused to whirl therein. The rotating hot air stream picks up the insecticidal material and carries it to the outer end of the cup where the air and material are discharged in a radial direction. It will be noted that the open end of the cup 52 extends to or slightly beyond the front face of the atomizer so that the discharge of the material takes place directly into the atmosphere and not into a confined space or chamber. As the material in the cup has been brought to a state of rapid rotation by the jets entering the tangential ports 33, this material is thrown outwardly by centrifugal force as soon as it passes out of the end of the cup. This will cause it to flow in a generally radial direction modified only by the axial velocity component resulting from its endwise issuance from the cup. The material in the cup is heated by the portion of the hot air entering through the ports 53 and by the heated wall of the cup itself. Preferably the inner wall of the cup is tapered slightly towards the open end, as shown in Fig. 3, although this is not essential. Hot air also flows around the outer cylindrical surface of the cup 52 excepting for the rear portion which is protected by a cylindrical shield 54, and the air passes out of the annular opening 55 in a direction substantially parallel to the axis of the cup, where it strikes the thin film of formulation at approximately right angles, and shears the material into minute particles. These particles can be varied from about .5 micron in diameter to about 60 microns and upwards depending upon the rate of flow of the formulation and the quantity, pressure and temperature of the hot air.

It will be observed that the introduction of the more or less heated mixture of formulation and air or gas issuing from the mouth of the cup into

the main body of heated air or gas issuing from the heater 34 through the annular opening 55, which may for convenience be termed the main air blast, takes place in the open atmosphere just as the mixture and air blast issue from their respective orifices, or even slightly beyond the actual margins of the orifices, and not in any duct or confined space. There is thus immediate freedom for expansion of the gases and vapors in radial directions as well as longitudinally outward from the atomizer. This has an important effect in producing a fog of desired particle size which has great persistence and spreading and penetrating power. At the same time the body of fog is more or less confined and directed outwardly by what may be thought of as an envelope of heated air issuing from the orifice 55 and forms a column of fog, so to speak, which may be directionally controlled and projected to considerable distances. Of course the generally radial discharge of the mixture from the mouth of the cup 47 causes a thorough intermingling of the same with the wall of the tubular envelope of the main blast, but the latter being in much larger volume than the mixture issuing from the cup has sufficient directive force to project the column of fog to the desired distance and in the desired direction.

The persistent quality and uniform character of the fog produced in the described manner is due, not only to the thorough breaking up and mixing of the formulation with the heated air, but also in part to the fact that the heated mixture of formulation with the relatively small body of the heated air in the cup is released into the larger part of the heated air or main blast in an entirely unconfined space, after both fluid streams have issued from their respective orifices.

The construction of atomizer described, and particularly the fact that in such construction the formulation mixture is discharged directly from the cup 52 into the atmosphere and main blast, causes the formulation material to be subjected to the relatively high temperatures obtaining in the cup for but a very short period of time. This is particularly important in the case of some formulation materials which would be injuriously affected if subjected to a more prolonged period of heating. Furthermore, the danger of carbonization in the cup and possible fouling of the apparatus is minimized.

As the fog produced by the atomizer above described issues directly as a stream or column into the open atmosphere the use of flexible hoses or the like for directing the stream is unnecessary as well as undesirable except under certain special conditions. In order that the stream may be orientated so as to project itself in the proper direction, it is desirable to mount the atomizer head on a universal mounting. In the construction shown a firm and simple mounting for the atomizer head is provided in which the latter is carried at the end of a short jointed duct which supports it directly from the heater 34 so that this jointed duct constitutes both the support for the atomizer head and the means for permitting its universal adjustment. A preferred construction for this purpose is as follows:

The duct 46, Figs. 1, 2, 3 and 4, has three sections 56, 57 and 58 which are so interconnected that the section 58 which carries the atomizer is capable of universal movement so that the atomizer may discharge in any predetermined direction. Section 56 is fixed to the combustion chamber 34 at its inlet end and has its outlet end se-

5.

cured to a connecting section 59 having a tapered cuff 60 which receives therein the inlet end of the section 57, the interfitting sections having registering ball bearing raceways which receive balls 61 introduced through filler opening 62 which is closed by plug 63. An annular sealing ring 64 between the end of section 57 and the axially opposed portion of section 56 prevents the escape of hot air from the conduit at the joint. With this arrangement, the inlet end of section 57 may be turned 360° with respect to the outlet end of section 56 about their common axis so that the outlet end of section 57 may be moved to any desired position in its circle of rotation. The outlet end of section 57 has an annular flange 65 which receives the inlet end of section 58, the interfitting parts also having ball bearing raceways which receive balls 66 introduced through a filler opening closed by a plug 67. An annular sealing ring 68 prevents leakage between the sections 57 and 58. Thus, section 58 may be turned through an angle of 360° with respect to the outlet end of section 57 about their common axis. Accordingly, with sections capable of rotation through arcs of 360° in directions at right angles to each other, the conduit 46 provides a mounting for the atomizer so that it can be positioned to discharge the formulation fog in any direction.

Means also are provided for locking section 57 of conduit 46 in the desired position with respect to section 56, and for similarly locking section 58 in any predetermined position with respect to section 57. As shown, such locking means comprises a U-shaped latch, Figs. 3, 4 and 6, having legs 69, each of which carries an extension 70 having at its outer end a tooth 71 which is shaped to fit the spaces between adjacent teeth 72 on the connecting section 58 and the section 57. A coil spring 73 surrounds the intermediate portion of each extension 70, the ends of which gear against a shoulder on the outer end portion of the extension and a guide 74, thus urging the latch toward locking position. The enlarged outer end portion of each extension moves in a guide 75 and a sleeve 76 extends between the guides 74 and 75 and covers the extension and the spring. The latch has a handle 77 by which it is grasped to move it to unlocked position against the action of springs 73. With this arrangement, when it is desired to change the direction in which the nozzle discharges the formulation fog or aerosol, the positions of the sections 57 and 58 are changed by moving the latches to unlocked position, moving the sections to the desired positions and then releasing the latches to lock the sections in the new positions.

The insecticidal or other treating material is introduced into a container 78, Figs. 7, 8, 9 and 10, through an opening in the upper end which is closed by a removable cover 79. The material is withdrawn from the lower portion of the container 78 through a pipe 80 having an opening 81 in the wall of the lower end thereof, the discharge end of the pipe 80 being connected to a fluid pump 82, Figs. 2 and 10, which is mounted on fuel tank 12 and is driven by gear 44. Pump 82 discharges the formulation into pipe 83 and into pipe 48 through which it is conducted to the atomizer 47. In passing through pipe 48, the material flows through a metering valve 84 and a control valve 85. A pressure gage 86 connected by pipe 87 to pipe 83 indicates the pressure of the material flowing to the atomizer. The

6.

pressure of this flowing material is controlled by a pressure control valve 88 in a pipe 89, the inlet end of which connects with supply pipe 83 through a branch pipe 90, and the outlet end of which connects with the upper end of a return pipe 91 which is disposed concentrically to, outside of and in spaced relationship to, the inlet end of pipe 89, as shown in Fig. 7. A safety valve 92 is connected to the juncture of pipes 89 and 90 through pipe 93, and to the outlet end portion of pipe 89 through pipe 94. Pipe 91 has an outlet opening 95 near its lower end which is disposed so that the material returned to the container is discharged in a direction substantially tangent to the wall of the container thereby setting the fluid in the container in rotation and resulting in continuous agitation of the insecticidal material. To maintain the discharge opening 95 in its proper tangent position, the upper end portion of the return pipe 91 has two pins 96, Fig. 8, fixed to the outer wall of the pipe in diametrically opposed relationship, and these pins are received in slots 97 in a boss 98 on the upper portion of the container. With the proper initial relationship between the discharge opening 95 and the pins 96 and slots 97, the discharge opening will be in the tangential discharge position as long as the pins 96 are in the slots 97.

In operation, the internal combustion engine 30, 31, 32, 33, 34, 35, 36, 37, 38, 39, 40, 41, 42, 43, 44, 45, 46, 47, 48, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98 is started, which drives the blower 32, the fuel pump 47, the magneto 43 and the insecticidal material pump 82. The blower supplies air to the combustion chamber 34, and the pump 47 supplies fuel thereto. In the combustion chamber 34 the air is heated to approximately 900° F. and is conducted to the atomizer 47 under a pressure of approximately 3 p. s. i. Pump 82 supplies insecticidal material to the atomizer where it is caused to rotate in a thin film in the cup 52 and to strike the main blast or surrounding envelope of hot air at approximately right angles upon its discharge from the cup with the result that the material is sheared into minute particles of controlled size. The sections of the conduit 46 are adjusted so that the insecticidal material will be delivered in the desired direction and to the specified area. The air pressure in the combustion chamber is varied by changing the speed of the blower 32 which is effected by varying the speed of the engine 26. The temperature of the gases delivered to the atomizer is varied by changing the quantity of fuel supplied to the combustion chamber by manipulation of the valve 40. Control of the rate of flow of the formulation and the quantity, pressure and temperature of the gases to the atomizer will control the size of the particles of formulation sprayed into the atmosphere. The size of these particles can be varied from about .5 to 60 microns, or from fog screen size to and including that obtainable by ordinary sprayers. The mass of the particles is such that the air currents carry them for relatively long distances and thus effect a uniform deposition of the insecticidal fluid over large areas. Experimental results have shown that these fine particles will not only come to rest on the top of plane surfaces, but due to eddy currents which are inherent in thick vegetation, will be deposited on the under sides of objects and into the tiniest crevices.

The formulation is delivered at a low pressure to the atomizer cup 52 and the quantity so delivered is regulated by manipulation of the control valve 88 independently of the speed of pump 82, the capacity of which is greater than the

maximum quantity of material required for the atomizer. Valve 85 is a quick opening and shut off valve. The excess material delivered by pump 82 is returned to container 78 through lines 90 and 89, or through lines 90, 93 and 94, depending upon the setting of the pressure control valve 88. The returned material is discharged tangentially to the tank wall, so that a continuous rotary motion of the insecticidal material is maintained in the container, thereby keeping suspension and suspensoids in a state of homogeneity.

In the form of the invention selected for illustration, the same fuel is utilized for the internal combustion engine 26 and the combustion chamber 34, but it will be understood that different fuels may be used.

With this machine, a very even deposit of minute particles is obtained at remote distances from the machine, thus providing an economical arrangement, both from the use of a minimum of insecticidal material and labor of application. The machine is compact, comparatively light in weight, and deposits the formulation more evenly, more widely and more rapidly than is possible by spray machines.

As used in the claims, the expression "insecticidal material" includes within its scope insecticides, fungicides, repellents and hormones, as well as other materials for accomplishing a similar or other purpose. As described above the heated gas delivered from the combustion chamber is largely air, such products of combustion as are present having no specific effect. The amount of products of combustion present depends simply upon the amount of fuel used for producing the heated blast. If the air is heated by an external source there would be no products of combustion, or a blast may be used containing any mixture of air and other gases. In the claims the blast is referred to as "hot air" which is intended to cover air alone or any mixture which may be employed of air and other inert gases or of such gases without air.

Inasmuch as the forms of the invention selected for illustration and description are preferred forms and are not intended to disclose the full extent of the invention, it will be understood that the invention is not to be limited excepting by the scope of the appended claims.

What is claimed is:

1. The method of producing an aerosol of treatment material in the open atmosphere, comprising mixing the material in liquid form with a relatively small amount of heated air, causing a large amount of heated air to issue under pressure from an orifice into the open atmosphere, introducing the heated mixture in fog forming proportions and under conditions producing minute subdivision of the treatment material into the air blast at the instant of its issuance from the orifice into the atmosphere and directing the resulting fog towards the area to be treated.

2. The method of producing an aerosol in the open atmosphere for application in the form of a fog to an area to be treated comprising producing a blast of heated air, splitting the blast into major and minor portions, discharging the major portion into the atmosphere, causing the minor portion of the blast to entrain a treatment formulation and combining the minor portion of the blast carrying the treatment formulation with the major portion of the blast under conditions producing minute subdivision of

the treatment formulation simultaneously with the discharge of the major portion of the blast into the open atmosphere.

3. The method of producing an aerosol of a treatment formulation in the open atmosphere for application in the form of a fog to an area to be treated which comprises discharging a blast of heated air into the atmosphere in the form of a tubular jet, causing a stream of formulation material to whirl rapidly about an axis concentric with the axis of the jet and discharging said formulation material into the center of said jet as the jet is discharged into the atmosphere whereby the whirling formulation material will be thrown outwardly into the tubular jet by centrifugal force and will form a fog therewith on issuance into the atmosphere.

4. Apparatus for producing an aerosol of insecticidal material comprising a heater, means for supplying air under pressure to the heater, an atomizer having a stationary cylindrical cup having an outlet end discharging into the open atmosphere, means for delivering insecticidal material into the cup, means for introducing heated air from the heater into the cup in such manner that it whirls therein and entrains the material and the whirling mixture is discharged from the outlet end of the cup in an outwardly deflected direction, due to centrifugal action, and means for conducting heated air from the heater to the area surrounding said atomizer cup and discharging it into the atmosphere around the outlet end of the cup in the form of a substantially continuous annular blast substantially parallel with the axis of the cup into contact with the whirling mixture of material and air to form an aerosol of said material.

5. Apparatus for producing an aerosol of a treating formulation for dispersion in the open atmosphere comprising a heater, means for supplying air under pressure to the heater, an atomizer having concentric discharge outlets discharging into the open atmosphere, means for delivering the treating formulation to the atomizer, means for introducing heated air from the heater into the atomizer in such manner that it whirls in the atomizer and entrains the formulation material therein and the mixture is discharged from the inner outlet of the atomizer while still whirling and means for discharging heated air from the heater into the atmosphere through the outer concentric outlet of the atomizer in a tubular jet surrounding and in contact with said whirling mixture to form an aerosol of said formulation material as it is discharged into the atmosphere, the axis of the tubular air jet being substantially coincident with the axis of whirl of said mixture, the direction of discharge of the tubular jet being substantially parallel with said axis of whirl.

6. An atomizer for producing an aerosol comprising a casing having inlet and outlet openings, a stationary substantially cylindrical member in the casing having one end closed and its other end projecting through said outlet opening out of contact with the wall thereof so as to provide an annular, substantially continuous outlet space from the chamber around said discharge end, means for introducing material to be atomized into said member adjacent said one end, the cylindrical member having a passage through the wall thereof adjacent said one end, means for supplying air under pressure through the inlet opening of said

casing for flow around said member and out said annular outlet space in a blast directed in a substantially continuous annular path parallel with the axis of the cup, some of the air under pressure passing through said passage into the cylindrical member, the passage being arranged to cause the air which flows therethrough to rotate in said member and carry with it the material therein, the construction and arrangement being such that the rotating material in said member is discharged from the discharge end thereof in outwardly deflected directions into contact with the blast of air flowing from said annular outlet space.

7. An atomizer comprising a casing having an inlet and an outlet opening, a stationary substantially cylindrical member in the casing having one end closed and the other end open and projecting into said outlet opening, and a tubular member projecting into the cylindrical member and having a closed outer end and an aperture in the side wall thereof through which material to be atomized is discharged radially into the cylindrical member adjacent the closed end thereof, the cylindrical member having an aperture in the wall thereof adjacent its closed end and disposed to discharge approximately tangentially to the inner wall of the cylindrical member, the construction being such that the material to be atomized is delivered into the cylindrical member at its closed end portion and is entrained in air delivered through the aperture in the wall thereof and is caused to whirl in said member and be discharged while whirling from the open end and into contact with a tubular air jet discharged from the outlet opening of said casing.

8. An atomizer head comprising a casing having an inlet opening at one side thereof, said casing having a large circular outlet orifice in the front thereof, a cup mounted on the back of the casing, a duct for the material to be atomized entering said cup through the bottom thereof and having a discharge opening for discharging the material to be atomized near the bottom of the cup, said cup having an opening extending through the side wall thereof in a substantially tangential direction for admitting air from the exterior to the interior of the cup, the open mouth of the cup extending through the orifice in the front of the atomizer head but out of contact with the walls of said orifice so as to provide an annular discharge opening from the casing concentric with the open mouth of the cup.

9. An atomizer head comprising a casing having an inlet duct at one side thereof, and having a large outlet orifice at the front thereof, a cup mounted on the back of the casing and extending transversely across the casing with its open mouth projecting through the orifice at the front of the casing but out of contact with the walls thereof so as to provide an annular outlet opening from the interior of the casing concentric with the mouth of the cup, a duct for material to be atomized entering the cup through the bottom thereof and projecting part way into the cup and having a closed outer end, said duct having a plurality of radial discharge openings in the side wall thereof, the cup having a plurality of tangential openings through the wall thereof in a region adjacent to the radial openings in the duct.

10. An atomizer comprising a casing having inlet and outlet openings, a stationary, substantially cylindrical member in the casing having

a discharge end projecting through said outlet opening out of contact with the wall thereof so as to provide an annular, substantially continuous outlet space from the casing around 5 said discharge end and parallel with the axis of said cylindrical member, said cylindrical member having a plurality of spaced passages through the cylindrical wall thereof with their discharge ends substantially tangent to the inner wall surface and discharging in a substantially circumferential direction into said member for admitting 10 a gaseous medium under pressure to pass from the casing into said cylindrical member and to flow around the interior of said member and out of the discharge end thereof, and means for introducing a liquid to be atomized 15 into said cylindrical member in a direction to impinge upon the inner cylindrical wall thereof, the construction and arrangement being such 20 that upon the introduction of a gaseous medium under pressure into said casing, some of the gases will pass into the cylindrical member through said substantially tangential passages and will rotate in the member, and cause the liquid 25 delivered thereinto to rotate in a thin film towards the discharge end of said cylindrical member where, due to centrifugal action, it will be discharged in outwardly deflected directions into 30 contact with a blast of the gaseous medium issuing from the casing through said annular outlet space.

11. Apparatus for producing an aerosol of insecticidal material comprising an atomizer, a container for the material, a pump for delivering 35 material from the container to the atomizer, the pump having a capacity larger than required to supply the material to the atomizer, means for returning the excess material to the container in such manner as to cause the material 40 in the container to move continuously in rotary motion, means for controlling the quantity of material supplied to the atomizer from the container, a combustion chamber, a fuel reservoir, a pump for supplying fuel to the combustion chamber, valve means for controlling the quantity of fuel supplied to the combustion chamber, a blower for delivering air to the combustion chamber, an internal combustion engine for operating said pumps and blower, an igniter 45 for igniting the fuel in the combustion chamber to heat the air supplied thereto by the blower, and a conduit connecting the combustion chamber and the atomizer, the conduit being constructed and arranged for universal movement 50 of the atomizer so that the atomized material may be discharged therefrom in any desired direction.

12. Apparatus for producing an aerosol of insecticidal material comprising a base, an internal combustion engine on the base, a blower on the base actuated by the engine, a combustion chamber on the base, a fuel burner for the chamber, a pump on the base actuated by the engine for delivering fuel to the burner, a conduit connecting the blower and the chamber through which air is delivered to the chamber and is heated therein, an atomizer, a pump on the base actuated by the engine for delivering insecticidal material to the atomizer, and a conduit connecting the chamber and the atomizer through which heated air is delivered to the atomizer for contact with the material to form an aerosol of the material, the last mentioned conduit supporting the atomizer and having connected sec-

11

tions which are movable with respect to each other.
